UNITED STATES PATENT OFFICE.

ABRAHAM DEE NORRID, OF HANSON, OKLAHOMA.

WASHBOARD.

1,205,252.

Specification of Letters Patent.

Patented Nov. 21, 1916.

Application filed February 12, 1916. Serial No. 77,891.

To all whom it may concern:

Be it known that I, ABRAHAM D. NORRID, a citizen of the United States, residing at Hanson, in the county of Sequoyah and

5 State of Oklahoma, have invented new and useful Improvements in Washboards, of which the following is a specification.

This invention contemplates the provision of a self-soaping wash board, embodying 10 among other features a novel construction of a board whereby the rubbing surface thereof coöperates with the soaping device to distribute the soap suds or solution over the entire area of the rubbing surface in 15 quick order, thereby rendering the duty of washing considerably less laborious.

The invention further aims to provide a board of the above mentioned character which will materially lessen the wear upon 20 the clothes during the rubbing operation.

In carrying out the invention I provide a novel construction of a soaping device whereby a cake of soap can be quickly and easily associated with the board for use, and 25 continuously maintained in contacting engagement with the rubbing surface of the board irrespective of the uneven wear which may occur upon the adjacent side of the soap, the device being simple in construction and easily manipulated for the purpose 30 intended.

Other objects will appear as the following description is read in connection with the accompanying drawings, the invention 35 residing in the novel combination, construction and arrangement of parts as defined in the claims.

In the drawings forming part of this specification like numerals of reference indicate similar parts in the several views and 40 wherein:

Figure 1 is a front elevation of a board constructed in accordance with my invention. Fig. 2 is a top plan partly in section 45 showing the position of the follower to facilitate the insertion of a cake of soap into the soap receptacle. Fig. 3 is a vertical sectional view. Fig. 4 is a horizontal sectional view. Fig. 5 is a rear elevation of the 50 board.

Before entering into a detail description of what is herein shown, I desire to have it understood that the drawings illustrate the preferred embodiment of the invention, and 55 that I do not limit myself to this precise

construction and arrangement of parts, as various changes may be resorted to when desired as fall within the scope of the invention as claimed.

Upon reference to the drawing it will be 60 noted that A indicates generally the board which consists of the side members 10 which are extended to provide supporting legs as in the usual construction of boards of this character, 11 the top, 12 the back and 13 the 65 rubbing surface. In this particular instance the rubbing surface consists of a plurality of closely associated rollers 14, journaled between the side members 11 for independent rotation, and each being provided with 70 a continuous spiral groove 15 extending throughout the entire length of the roll.

With a board of this construction I employ a soaping device comprising a follower 75

16 adapted to be arranged for sliding movement within a receptacle 17 mounted upon the back 12 for the reception of a cake of soap, the receptacle being in open communication with the rollers 14 for the purpose of having the soap continuously engage the latter. The follower 16 is carried by the free end of a lever 18 fulcrumed at a point in 80 its length upon a suitable bracket 19 secured to the back of the board, the opposite end of the lever having pivotal connection with an operating arm 20 which passes through

a suitable opening in one of the side members 10 and projects a considerable distance forwardly of the board, terminating to provide a manipulating portion 21. In the 85 normal position of parts the operating arm 20 extends forwardly of the board, and as the soap diminishes in size the arm 20 is moved rearwardly thereby rocking the lever 18 upon its fulcrum and moving the follower 16 together with the soap into engagement with the rollers 14. One of the 90 longitudinal edges of the operating arm 20 is provided with a toothed surface 22, the teeth being beveled in the proper direction to permit the resilient catch 23 to automatically engage the proper tooth to hold the parts fixed in adjusted position.

Manifestly by reason of the fact that the 95 rollers 14 are mounted for independent rotation, the rubbing operation is not only rendered considerably less laborious, but wear upon the clothes during such operation is reduced to a minimum. As the rollers are 100 rotated during the rubbing operation the 105

110

soap suds or soap solution is received within the grooves 15 of certain of the rollers at their point of contact with the soap, and expeditiously fed through the grooves trans-
5 versely and longitudinally of the board and over the entire area of the rubbing surface.

It will be noted that the follower 16 is pivotally connected to the free end of the lever 18 by means of a pair of spaced lugs
10 25 secured to the follower, which connection permits of the latter being swung to the position shown in Fig. 2, to permit of a cake of soap to be easily positioned within the receptacle 17. In addition to this func-
15 tion, the pivotal connection between the follower 16 and lever 18, allows the follower to assume different angular positions within the receptacle 17 so as to engage the soap throughout its entire area, should the cake
20 of soap become worn to a greater extent at one end than the other and thereby assume an inclined position within the receptacle. However with the construction hereinabove described, the wear upon the soap will be
25 very evenly distributed, so that the soap will uniformly diminish in size to permit the entire cake of soap to be used.

The board is simple in construction, and the soaping device easily manipulated in the
30 manner hereinabove set forth.

Copies of this patent may be obtained for five cents each, by addressing the "Commissioner of Patents,
Washington, D. C."

What I claim is:—

1. A self-soaping wash board including a soap receiving compartment communicating with the rubbing surface of the board, a lever fulcrumed at a point in its length, a follower pivotally associated with the free end of the lever and movably arranged within said compartment, an operating arm connected with the opposite end of the lever, and means for automatically locking 40 said arm in adjusted position.

2. A self-soaping wash board including a soap receiving compartment communicating with the rubbing surface of the board, a lever fulcrumed at a point in its length, a follower pivotally associated with the free end of said lever and movably arranged within said compartment, an operating arm connected with the opposite end of said lever and having a toothed surface, and a 45 spring coöoperating with said toothed surface for automatically locking said arm in adjusted position.

In testimony whereof I affix my signature in presence of two witnesses.

A. DEE NORRID.
